[57] CLAIM

The ornamental design for a satellite radio receiver, as shown.

DESCRIPTION

FIG. 1 is a front, top and right side perspective view of a satellite radio receiver showing our new design;

FIG. 2 is a front elevational view;

FIG. 3 is a right side elevational view;

FIG. 4 is a left side elevational view;

FIG. 5 is a view like FIG. 1 of another embodiment of a satellite radio receiver showing our new design wherein there are three instead of four round dials, two instead of one right buttons and no indicating window above a round dial;

FIG. 6 is a front elevational view thereof;

FIG. 7 is a view like FIG. 3 thereof; and

FIG. 8 is a view like FIG. 4 thereof.
